RAILWAY CAR TRUCK

**Stacy B. Haseltine, La Grange, Ill., assignor to
W. H. Miner, Inc., Chicago, Ill., a corporation
of Delaware**

Application May 19, 1943, Serial No. 487,544

5 Claims.

(Cl. 105—197)

This invention relates to improvements in railway car trucks.

One object of the invention is to provide means supplemental to the usual truck springs of a railway car truck for snubbing or dampening the action of the springs, thereby reducing the oscillations and vibrations of the same to such an extent that the car and its lading will be protected against damage.

Another object of the invention is to provide a snubbing means comprising relatively slidable friction elements movable with the bolster of the car and interposed between the bolster and bolster guides of the truck side frames and having frictional sliding engagement with the guides, wherein the friction elements are provided with angularly projecting flanges disposed between the underneath side of the bolster and the truck springs and having rocking engagement with said underneath side of the bolster, whereby the pressure exerted by the springs rocks the friction elements outwardly to press the same against the bolster guides.

Other objects of the invention will more clearly appear from the description and claims herein-after following.

In the drawing forming a part of this specification, Figure 1 is a vertical sectional view through one of the side frame members of a railway car truck, illustrating my improvements in connection therewith, the side frame being partly broken away, said view corresponding substantially to the line 1—1 of Figure 2. Figure 2 is a horizontal sectional view, corresponding substantially to the line 2—2 of Figure 1. Figure 3 is a perspective view of a friction plate element employed in my improved railway car truck structure.

In said drawing, 10 indicates one of the side frame members of a railway car truck. The side frame 10, as shown, is in the form of a casting and has top and bottom members 11 and 12 connected by spaced vertical sections 13—13 forming guides for the truck bolster. As will be understood by those skilled in this art, the truck includes two side frame members 10—10, a truck bolster 14, a transversely disposed spring plank 15 connecting the two side frame members and supported at opposite ends on the bottom members 12—12 of the side frames 10—10, and truck springs 16—16. The bolster 14 has its opposite ends guided between the vertical sections 13—13 of the truck side frames 10—10 and is supported by the springs 16—16. As most clearly shown in Figure 2, the sections 13—13 are inwardly offset at their upper end portions to provide guides 17—17 which cooperate with guide seats 18—18 at the sides of the bolster 14. The truck springs 16—16 are supported directly on the bottom members 12—12 of the side frames 10—10, the usual bottom spring follower plate 19 being interposed

between each truck spring cluster and the spring plank.

In carrying out my invention I provide the usual top spring follower plate 20 and a pair of rockable friction elements A—A which have sliding engagement with the bolster guides of the truck side frames and with which the truck springs cooperate to press the same against said guides.

10 The top and bottom spring plates 20 and 19 are of the usual type employed in railway car trucks and bear respectively on the top and bottom ends of the springs 16—16—16—16, each plate having the usual projecting bosses 21—21 for centering the springs.

15 The rocking friction elements A—A are of like design, each comprising a relatively wide baselike foot portion 22 of substantially rectangular outline and an upstanding platelike portion 23 at the outer edge of the base. The corners of the base are preferably rounded, as shown most clearly in Figure 3. The plate portion 23 is of lesser width than the base 22 and the base portion projects beyond the opposite side ends of the plate 23.

20 The elements A—A are disposed at opposite sides of the bolster, with the base portions 22—22 thereof interposed between the underneath face of the bolster and the top spring follower plate 20, and the platelike sections 23—23 interposed between the sides of the bolster 14 and the bolster guides 17. As shown in Figures 1 and 2, the bolster guide seats 18 have inset portions or pockets 24—24 which accommodate the plate sections 23—23. The plate section 23 of each element is of lesser height than the vertical thickness of the bolster 14 and corresponds in width to the width of the guide 17. Each guide 17 has the usual wear plate 25 covering the same.

25 30 35 40 45 50 The base portions 22—22 of the friction elements A—A are inclined to the horizontal, as shown in Figure 1, that is, the foot or base portion 22 of each element is disposed at an angle to the plate section thereof which is slightly greater than a right angle. The base portions are thus inclined downwardly and inwardly away from the underneath side of the bolster, thereby providing for rocking engagement between the elements A—A and the underneath side of the bolster.

55 Each base portion 22 is of such a width that it overlies two of the springs of the spring cluster, that is, the two springs at the corresponding side of the bolster. Sufficient clearance is provided between the opposed inner edges of the base portions of the pair of friction elements to permit rocking of the bases toward the bolster without danger of contact or binding of the bases with each other.

As will be evident, the flanges or base portions 22—22 of the elements A—A are subjected to

the pressure of the springs 16-16 and the tendency is to rock these elements outwardly toward the bolster guides to press the friction surfaces of the plate sections 23-23 thereof into tight frictional contact with the friction surfaces provided by the wear plates 25-25.

The operation of my improved dampening device is as follows: Upon relative vertical movement of the bolster 14 with respect to the side frame 10, the coils of the cluster or group of springs 16-16 are compressed between the bolster and the spring plank. At the same time the friction elements A-A are forced to slide vertically along the bolster guides, moving in unison with the bolster 14. A friction snubbing action is thus produced during compression of the springs. During recoil of the springs, the friction elements A-A move upwardly with the bolster 14, and due to frictional engagement with the guides 17-17 dampen the recoil action. During both compression and expansion of the truck springs the friction elements are urged into tight frictional contact with the friction surfaces of the bolster guides by the action of the springs which exert pressure on the base flanges 22-22 of said elements A-A to rock the latter outwardly away from the bolster.

As will be evident, as the springs are being compressed the frictional resistance produced by movement of the elements A-A with respect to the bolster guides is augmented due to the increased pressure of the springs on the base flanges or arms 22-22. As the springs recoil, the frictional resistance is progressively reduced due to the reduction of the spring pressure on the rocking friction elements.

I have herein shown and described what I now consider the preferred manner of carrying out my invention, but the same is merely illustrative and I contemplate all changes and modifications that come within the scope of the claims appended hereto.

I claim:

1. In a railway car truck including a truck side frame having spaced bolster guides, the combination with a vertically movable bolster having a horizontally disposed underneath surface; of a cluster of springs supporting said bolster; and rocking friction elements movable with the bolster, said friction elements having friction plate portions interposed between the bolster and bolster guides and slidably engaging the bolster guides, said elements having base portions having engagement with and fulcrumed directly on said underneath surface of the bolster, at opposite sides of the latter, and acted on by the springs to rock said plate portions against the guides.

2. In a railway car truck including a truck side frame having spaced bolster guides, the combination with a vertically movable bolster having its underneath side at right angles to said guides; of a pair of friction elements movable with the bolster, each of said elements having an upright friction plate section of uniform thickness throughout its length, said plate section being interposed between the corresponding side of the bolster and the cooperating bolster guide, and a flat base flange of uniform thickness throughout its length projecting beneath the bolster integral with the plate section and bearing on the underneath side of the bolster, said base

section being disposed at an angle to said plate section which is greater than a right angle; springs supporting said bolster on the side frame; and a spring plate interposed between the upper ends of the springs and the base flanges of the friction elements.

3. In a railway car truck including a truck side frame having spaced vertical bolster guides, the combination with a vertically movable bolster having its underneath surface disposed at right angle to said guides; of a cluster of springs supporting the bolster on the side frame; and a pair of friction elements at opposite sides of the bolster, each of said elements having a flat upright friction plate section and a flat base flange at the lower end of said plate section integral therewith, said base flange being angularly disposed to said plate section, the angle between said flange and plate being greater than a right angle, said friction plate being interposed between the corresponding side of the bolster and the adjacent vertical bolster guide and having sliding frictional contact with said guide, said base flange projecting beneath the bolster and bearing at its outer end portion on the underneath side of the latter and being interposed between the springs and the bolster.

4. In a railway car truck including a truck side frame having spaced bolster guides, the combination with a vertically movable bolster having pockets at opposite sides thereof opposed to the bolster guides of the side frame; of a cluster of springs supporting said bolster on the truck side frame; and a pair of friction elements having upstanding plate sections accommodated in said pockets of the bolster, said plates having sliding frictional engagement with the bolster guides, said elements having laterally, inwardly projecting base flanges at the lower ends of said plate sections, integral with the latter, said base flanges being interposed between the underneath side of the bolster and the top end of said spring cluster, said flanges having the top surfaces thereof which contact the bolster disposed at an angle to the upstanding sections thereof, which angle is greater than a right angle.

5. In a railway car truck including a truck side frame having spaced bolster guides, the combination with a vertically movable bolster, said bolster having a substantially flat underneath surface; of a cluster of four springs supporting said bolster on the side frame; and a pair of rocking friction elements at opposite sides of the bolster movable therewith, said friction elements having upstanding plate portions interposed between the bolster and the bolster guides and slidably engaging said guides, said elements having laterally inwardly projecting base portions extending beneath the bolster, the base portion of one of said elements being interposed between the upper ends of two of said springs and the bottom of the bolster at the corresponding side of the latter, said base portion and the underneath surface of the bolster diverging inwardly, and the base portion of the other of said elements being interposed between the upper ends of the remaining two of said springs and the bottom of the bolster at the corresponding side of said bolster, said last named base portion and the underneath surface of the bolster diverging inwardly.

STACY B. HASELTINE.
